VACUUM AND PRESSURE PUMP

Application filed July 20, 1927. Serial No. 207,181.

My invention relates to pumps and it has for a purpose the provision of a pump which economically produces a high degree of vacuum and pressure by rapidly revolving an obstruction in a liquid. My invention is especially designed for the evacuation of fluids from vessels; or for a rapid removal of vapors from the surfaces of liquids or solids contained in a closed vessel; or to generate high pressures of fluids; or to perform all of the foregoing functions simultaneously.

The pump is designed to take advantage of the fact that an obstacle moving through a liquid at high speeds tends to produce high positive pressures in advance of the obstacle and at the same time low negative pressures in the rear of the obstacle. When the velocity of travel is sufficiently high the liquid is unable to fill immediately the space left in the path of the obstacle and a vacuum or partial vacuum is thus created.

The pump is so designed that an obstacle is made to rotate in a liquid at high speed in such a way that a vacuum is created in the wake of the obstacle. A path is provided for the passage of a gas, vapor or liquid to this vacuum space and the fluid expands and fills the vacuum space by virtue of the kinetic energy of the molecules of the fluid, or by virtue of any pressure of a mechanical sort which may tend to force the fluid along the passage provided leading to the vacuum space. The obstacle creating the vacuum space is so designed as to produce a turbulence in the surrounding liquid, causing the gas, vapor or liquid to be trapped and held in the liquid while the obstacle continues its motion. The fluid now rises in the surrounding liquid due to its lower specific gravity, and escapes at the surface of the liquid. Here it may be trapped and used to exert pressure if desired, or it may be preserved by inclosure in a suitable container. The liquid surrounding the moving obstacle is held as nearly stationary as is possible by means of vanes, screens, or other means. These means of holding the liquid are so designed as to counteract the tendency of the rotating obstacle to generate rotary

and centrifugal force and motion in the surrounding liquid. The pump is of such a nature that two or more stages can be operated in series, all stages being operated by the same shaft and contained in the same vessel.

I will describe only four forms of pumps, each embodying my invention, and will then point out the novel features thereof in claims.

In the accompanying drawings:

Figure 1 is a view showing in vertical section one form of pump embodying my invention;

Fig. 2 is a horizontal sectional view taken on the line 2—2 of Fig. 1;

Fig. 3 is an enlarged plan view of the rotator embodied in the pump shown in Fig. 1;

Figs. 4, 5, and 6 are sectional views taken on the lines 4—4, 5—5, and 6—6 respectively, of Fig. 3;

Fig. 7 is a fragmentary vertical sectional view of a multi-stage form of pump embodying my invention;

Fig. 8 is a horizontal sectional view showing another form of pump embodying my invention;

Fig. 9 is a horizontal sectional view showing another form of rotor adapted to be substituted for the rotor for the pump shown in Fig. 1 and embodying my invention;

Fig. 10 is a sectional view taken on the line 10—10 of Fig. 9; and

Fig. 11 is a detail view of one of the agitators embodied in the rotor shown in Figs. 9 and 10.

Similar reference characters refer to similar parts in each of the several views.

Referring to the embodiment shown in Figs. 1 to 6 inclusive, 15 designates the stator of the pump closed at its top by a cover 16 and provided at its bottom with an opening 17 disposed axially thereof and through which extends an intake pipe 18, the latter being of the form shown in Fig. 1 and provided with a valve 19 by which the delivery of fluid to the stator can be controlled at the will of the operator. The pipe 18 is adapted for connection to any source of fluid

such as a vessel containing a fluid and from which vessel it is desired to remove the fluid. That portion of the pipe 18 which extends upwardly through the opening 17 is sealed 5 against the passage of liquid from the stator and around the pipe by a suitable gasket 20 secured in the manner illustrated in Fig. 1. The cover 16 is provided with an air and liquid tight bearing 21 of sufficient extent 10 and rigidity to prevent vibration of a shaft 22 which is journaled therein. The upper end of the shaft 22 is provided with a pulley 23 by which the shaft is adapted for connection to a motor so as to be driven thereby. 15 The lower end of the shaft is suitably secured to a rotor designated generally at R, and by which rotary motion is imparted thereto continuously in one direction. The rotor R in the present instance comprises 20 a pair of tubular arms 24 curved in opposite directions from their point of connection to each other and rearwardly with respect to the direction of rotation of the rotor in order that their free ends will be disposed in 25 trailing relation to the remainder of the arms when the rotor is in operation. The curvature of the arms is such that they combine to form an ogee and although I have shown only two arms it is to be understood 30 that any number of arms may be provided without departing from the spirit of my invention.

The construction of the two arms is identical, and either arm is shown in Fig. 5 as a 35 stream line cross-section to reduce to a minimum the resistance of the liquid as presented to the arm in its rotative movement. This stream line portion of the arm merges into a circular portion as it progresses toward the free end of the arm as will be seen 40 from Fig. 6. The circular portion in turn merges into a conical terminal portion indicated at 25, and as shown in Figs. 3 and 4, this terminal portion being provided upon 45 its outer periphery with an annular series of projections or vanes 26 disposed spirally and projecting beyond the end of the arm with their free ends terminating abruptly or substantially at right angles to the projections. As shown in Fig. 1, the end 25 of 50 one arm is curved upwardly while the end of the other arm is curved downwardly so that when the rotor is in operation the two ends will travel in different horizontal planes.

At the point of connection of the two arms 24 with each other, a tubular spindle or tube 27 depends therefrom and into the adjacent vertical portion of the intake pipe 18. This 55 spindle is provided on its inner periphery with spirally arranged ribs 28 designed for the purpose of elevating a liquid from the pipe 18 upwardly into the arms 24 under the rotative movement of the rotor. This spindle or tube has a rotating fit within the

pipe 18 to prevent a relatively large flow of liquid between the two but allows enough to operate without friction.

As illustrated to advantage in Figs. 1 and 2, the stator 15 is provided interiorly with 70 vanes and partitions for minimizing movement of a liquid contained in the stator in order that the rotor R may operate efficiently in producing vacuums within the liquid, as will be described hereinafter. 75

In the present instance I provide partitions 29 arranged one above the other within the stator and all perforated and formed with axial openings to receive the shaft and rotor spindle. At the under sides of the 80 partitions spiral vanes 30 are secured, and these vanes are perforated as illustrated in Figs. 1 and 2. Between the partitions and the spiral vanes are vertical vanes 31 arranged at intervals about the inner periphery of the stator as illustrated in Fig. 2. 85

When the rotor R is in operation the level of the liquid contained in the stator is above the uppermost partition 29, as illustrated by the dash line 32 in Fig. 1, so that all of the 90 partitions and vanes are submerged. The partitions function to check rising movement of the liquid and yet allow the escape of the fluid being pumped. The spiral vanes 30 counteract rotational and centrifugal motions of the liquid, while the vanes 31 further check rotational movement of the 95 liquid.

The fluid which escapes through the liquid 100 in the stator is trapped in the stator above the liquid, but can be released as required through an outlet pipe 33 extended through the cover 16 and provided with a valve 34 for controlling the exhaust of pressure fluid.

The operation of the pump is as follows: 105

With the rotator R rapidly rotating in the direction of the arrow in Fig. 3 and the pipe 18 connected to the source of fluid which it is desired to pump, vacuum spaces will be formed in the liquid contained in the stator directly in the wake of the arm ends 25. Resultant of these vacuum spaces an induced suction or negative pressure is created within the tubular arms 24 which acts to draw fluid from the pipe 18 through the spindle 27 and into the arms 24, the fluid finally discharging from the arm ends 25 into the stator liquid. As the space between the pipe 18 and the tube 27 is such as to prevent a relatively large flow of liquid 110 therethrough, it will be evident that the actual volume of liquid thus passing downward between the two tubes 27 and the pipe 18 is very much smaller than the total volume of fluid passing upward through the tube. Hence, it is impossible for the liquid 115 to permanently fill the tube. Further, as the pressure in the rotor is at all times lower than the pressure in the pipe 18, the fluid in the pipe tends to force a passage into the 120

125

130

5 tube so that should the tube be temporarily blocked by the pump liquid, the fluid in the pipe will force the liquid ahead of it and thus open the tube to the interior of the rotor. The projections 26 produce a turbulence in the liquid surrounding the vacuum spaces thereby causing the incoming fluid to be trapped and held in the liquid while the rotator continues its motion.

10 These projections are constructed so as to offer as little resistance as possible to the motion of the rotor arms in the liquid except the very ends of the projections which abruptly terminate so that a vacuum is created due to the inability of the liquid to stream around the projection ends and fill the space behind such ends. As previously described, these projections extend beyond the conical arm end, the vacuum tending to draw the liquid through the opening between the projections which, coupled with the whirling created, acts more effectively to trap and remove the fluid emerging from the arm.

15 The fluid is subsequently liberated so that it now rises in the liquid due to its lower specific gravity and finally escapes at the surface of the liquid. Here it may be trapped by closing of the valve 34 so that a pressure of the fluid is built up within the stator, and this fluid pressure may be released as desired to perform any useful function. By reason of the vanes and partitions the liquid surrounding the rotor is held as nearly stationary as is possible so as to counteract the tendency of the rotor to generate rotary and centrifugal force in the liquid and to thus reduce the vacuum creating property of the liquid and rotor.

20 In the foregoing operation, I have described a pump as handling fluids, and it will be understood that the pump is capable of pumping any gas, vapor or liquid of a specific gravity which is lower than that of the pumping liquid employed or the same.

25 Referring now to Fig. 7, I here show another form of pump embodying my invention, to illustrate that a pump of the general form shown in Fig. 1 can be designed in two or more stages and operated in series. In this embodiment of my invention the stator 15 is provided with a single partition 35 formed with an axial opening through which the rotor shaft 36 extends. The shaft 36 is constructed to provide two tubes or spindles 37 and 38 corresponding in construction to the spindle 27 in that they are provided interiorly with spiral ribs 28 for the elevation of liquids and have a rotating fit to prevent a relatively large down flow of liquid therearound but to allow enough to operate without friction. Between the spindles the shaft is provided with arms 24^a, and above the spindle 38 the shaft is

30 provided with arms 24^b. These arms 24^a and 24^b are identical in construction to the arms 24 of the first form of pump and hence when rotated operate in the same manner. The shaft 36 is blocked by inserts 39 at points directly above the arms 24^a and 24^b to prevent passage of the pump fluid upwardly through the shaft and in a manner to cause the fluid to be discharged through the arms. The spindle 38 is provided with 70 openings 40 at a point below the partition 35 through which the pump fluid as discharged from the lower rotor will pass into the spindle 38 for ultimate discharge from the arms 24^b of the upper rotor.

35 In operation, the fluid to be pumped enters through pipe 18 and passes through the first stage exactly as described in connection with the pump shown in Fig. 1. After ejection from the ends of the arms 24^a the fluid rises through the liquid in the stator beneath the partition 35, the level of which liquid is indicated by the line 41. It then enters the spindle 38 through the openings 40 and similarly passes through the arms 24^b of the upper rotor. Any surplus pump liquid beneath the partition 35 is automatically removed to a point above the partition and the level automatically maintained by the position of the openings 40. When the pump is stopped the part of the liquid above the partition 35 will pass through the rotor arms and down through the spindle 38 into the chamber beneath the partition 35 possibly filling the air space above the liquid in the lower chamber; but this liquid is pumped back into the upper chamber as soon as the pump resumes operation. Leakage of the pump liquid around the spindles 37 and 38 is not a serious objection as it is immediately forced back into the corresponding chamber of the stator.

40 Referring now to Fig. 8, I have here shown a third form of pump embodying my invention, which comprises a stator 42 adapted to contain a liquid and provided with a fluid inlet 43. Within the stator is a rotor 44 which is adapted to be rotated in the direction of the arrow by any suitable means. This rotor comprises an annular body 44^a provided with radial blades 44^b arranged at regular spaced intervals about the body. This pump provides for a rapid circular motion of the liquid contained in the annular space between the stator and rotor. The fluid to be pumped is admitted at the inlet 43 and is trapped by the moving liquid at the opening 45 between the stator and a deflecting plate 46. This plate 46 is provided with projections 47 at its inner end for the purpose of producing the necessary turbulence. The incoming fluid rises above the surface of the pump liquid and escapes through a high pressure opening (not shown).

Referring to Fig. 9, I have here shown a third form of rotor embodying my invention. This rotor comprises a disc-shaped body 48 which may be made solid or hollow, as shown. It is interiorly constructed to provide an axially and vertically disposed passage 49 which communicates with radial passages 50. The passages 50 in turn communicate at their outer ends with channels 51 formed in the periphery of the body 48 and extending in opposed directions from the passages 50. These channels are of graduated depth with the deep ends communicating with the passages 50.

In practice, this rotor, when rapidly rotated in a counterclockwise direction in the stator 15, functions in the same manner as that described in connection with the rotor R of the pump shown in Fig. 1. The fluid being pumped rises within the passage 49 and is discharged radially through the passages 50 into the vacuum spaces formed in the wake of the channels 51. The required whirling motion of the pump liquid surrounding these vacuum spaces is generated by the provision of bifurcated plates 52 secured to the periphery of the body 48 by bolts 53 so that the projections formed by the bifurcations are disposed at the deep ends of the channels 51.

An important feature of my invention is that the pump after reaching a constant speed will produce a definite pressure or vacuum, and once such pressure or vacuum is attained the pump will not operate to increase it beyond this maximum so that it may be said that the pump ceases to function. This is contrary to present pumps where the pressure or vacuum continues to build up or increase after the pump has attained a constant definite speed.

Another important feature of my invention is the adaptation of the pump as an evaporator or gasifier of liquids. In this adaptation the inlet valve 19 is closed and with the rotor rapidly rotating in a body of liquid, for example gasoline, the vacuum spaces produced in the wake of the arm ends 25 causes the liquid to evaporate therein thus converting it into a gas or vapor which rises through the latter and is compressed above the liquid providing the outlet valve 34 is closed.

Although I have herein shown and described only four forms of vacuum and pressure pumps embodying my invention, it is to be understood that various changes and modifications may be made herein without departing from the spirit of the invention and the spirit and scope of the appended claims.

I claim:

1. A pump comprising a stator adapted to contain liquid and having a fluid inlet, and a rotor comprising a tubular spindle

communicating with the inlet, and arms fixed to the spindle for rotation in the liquid, said arms being rearwardly curved in respect to their direction of rotation and tubular with their free ends open and provided with spiral projections for the purpose described.

2. A pump comprising a stator adapted to contain liquid and having a fluid inlet, and a rotor comprising a tubular spindle communicating with the inlet, and arms fixed to the spindle for rotation in the liquid, said arms being rearwardly curved in respect to their direction of rotation and tubular with their free ends open and provided with spiral projections extending beyond the ends and having abruptly terminating free ends.

3. A pump comprising a stator adapted to contain liquid and having a fluid inlet, and a rotor comprising a tubular spindle communicating with the inlet and arms connected to the spindle for rotation in the liquid, each arm having that portion adjacent the spindle of stream line cross-section and merging into a portion of circular cross-section, and the latter portion merging into a conical terminal portion.

4. A pump as embodied in claim 3 wherein, the terminal portion is provided with exterior projections for producing a turbulent motion of the liquid beyond the terminal portion.
